UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

METAL STRUCTURE FOR RAILWAY CARS.

Application filed June 7, 1926. Serial No. 114,247.

Reference is made to the accompanying drawings, which illustrate the preferred form of the invention, though it is to be understood that the invention is not limited to the exact details of construction shown and described, as it is obvious that various modifications thereof within the scope of the claims will occur to persons skilled in the art.

My invention relates to the construction of railway cars and more particularly to metal end structures or walls for railway cars made of one or more metallic plates or panels formed with integral reinforcing, stiffening and bracing embossments or corrugations.

It is well known that the end walls of railway cars are more likely to be broken or otherwise injured than the side walls. This is due to the inertia thrusts and pressures caused by the shifting of the cargoes when the train starts or stops. These thrusts may be local, tending to distort the end in some particular spot, as, for example, when a piece of piping or lumber shifts lengthwise imparting a blow against the end wall of the car; or there may be a general tendency to break out the end wall as a whole or tear it away from the framing. For the purpose, therefore, of greater strength and durability, car ends have been constructed of metal plates corrugated or formed with ribs to impart the desired strength, rigidity and resiliency.

One of the principal objects of my invention is to provide a corrugated or embossed metallic end structure for railway cars in which the corrugations or embossments have a configuration and arrangement that impart to the structure a maximum capacity for resisting cargo thrusts, both local and general, static or quiescent, and with sufficient resiliency to prevent permanent distortion due to the thrusts of the loads, with a minimum weight of metal. It is important that structures of this sort should be as light as possible, consistent with strength and durability, both for reasons of economy in manufacturing cost and also to keep the weight of the car at a minimum.

A further object is to provide a corrugated metallic wall element that is practically possible to manufacture. A further object is to provide a metallic wall element with corrugations that resist to a greater degree tor-

sional stresses, as well as brace the element, and the car end against diagonal side thrusts or weaving.

The combination of the embossments, ribs or corrugations comprising the reinforcement formed in the metallic plate is disclosed and claimed in my separate application for patent, Serial No. 595,634, filed October 19, 1922, and this application for patent discloses and claims the specific advantages and constructions when such a reinforced metallic plate is applied to a car with the corrugations or reinforcements positioned vertically or substantially so, i. e., extending from adjacent the floor of the car (or end sill) to adjacent the roof (or end plate.) The metallic reinforced plates comprising the wall are usually connected along vertical lines, and the middle plate or plates may be made of thicker metal than those adjacent the side of the car and the corrugations in the middle of the car end wall may be made stronger than those elsewhere by being made deeper or wider or both. Also the corrugations in the middle of the car end wall may be made longer to eliminate any flat space between the upper end of the corrugations and the end plate or roof of the car.

The maximum pressure and stress on a car end wall is about two feet above the floor and adjacent the middle of the car. The corrugations are a series of parallel beams and when positioned vertically the lower ends of the beams are supported by the underframe which is the backbone of the car and the upper ends are supported by the end plate. A beam should have its maximum strength adjacent its point of maximum stress, therefore, I prefer to have the strongest part of the individual corrugation, as well as the entire end wall, about two feet from the floor or about one-fourth the length of the corrugation.

 Fig. 30 is a section on line 30—30 of Fig. 26.
 Like characters of reference designate like 40 parts.
 The end wall structure shown in the above figures comprises a panel composed of a corrugated metal plate or plates.
 Referring to Figs. 1 and 2. The corrugated plates 1, 2 and 3 extend across the car from top to bottom and are formed with integral flanges 4 along the vertical edges which overlap and are secured to the side walls 5 of the car by any suitable means.
 The top edge of the end wall is secured beneath the fascia boards 7 and the meeting edges of the plate overlap and are secured together by rows of rivets 8 and the lower edge of the end wall is secured to the end sill 9. Nailing strips are positioned within the corrugations and secured thereto by bolts and lining 11 is preferably nailed to the strips.
 Figs. 3 and 4 show a modified form of the invention applied to a gondola type of car, 60 wherein only one plate 12 is used to form the end panel which extends from side to side of the car and is provided along the vertical edges with flanges 13 which overlap and are secured to the side walls 14 by any suitable means. The top edge of the plate is secured to the top chord 15 by rivets 16, while the lower edge is secured by rivets 17 to the end sill 18.
 While the corrugations are shown pressed outwardly, it is understood that the corrugations or embossments may be pressed inwardly, or partially inwardly and partially outwardly, from the original plane of the plate. The plates or panels may be applied to any type of railway car.
 Figs. 5 to 9 inclusive show the reinforced plate provided with a plurality of parallel vertical corrugations or embossments, each embossment comprising a plurality of sinuous minor corrugations 23 which are spaced apart distances 22 substantially equal to their respective widths and the part of the plate 30 between adjacent minor corrugations is also sinuous so that these minor corrugations merge together to form a contiguous sinuous configuration (Fig. 9) symmetrical in cross section about a line midway between the outermost portions of these minor corrugations so that this line is the neutral axis 80 of the section. Such a section is very resilient and has a spring like action under loads, and, furthermore, produces a very strong section for the amount of metal used. These minor corrugations merge into the plane of the plate by means of terminal portions 31 of any desired formation. A plurality of such minor corrugations merge together between their ends adjacent the floor of the car to form a plurality of fewer major corrugations 21 with preferably flat apices 25 which are 90 spaced apart distances substantially equal to their respective widths and the part 32 of the plate between these major corrugations is also preferably flat, thus forming a configuration (Fig. 7) symmetrical in cross section about a line midway between the outermost portions of these major corrugations so that this line is the neutral axis of the section. Such a section is stronger and relatively rigid 100 as compared with the section of the sinuous minor corrugations because more metal is positioned away from the neutral axis. By such an arrangement a wall is provided which is relatively rigid adjacent the floor of the car and relatively resilient adjacent the top 105 and bottom of the end wall. The secondary oppositely projecting rib 22 formed by the merging of the two adjacent minor corrugations 23 is equal in width to the adjacent minor corrugations at 23 and decrease in 110 width as the minor corrugations merge together to form the major corrugation 21. These secondary oppositely projecting ribs 22 also preferably decrease in depth so that any concentrated stretch of metal is eliminated where the minor corrugations merge together.
 Figs. 10, 11 and 12 are a detail enlargement of portions of the plate taken on lines 7, 8 and 9, respectively, of Fig. 5. Fig. 10 120 130

shows the relatively wide flat apices 25 of the major corrugations 21, the sloping sides 26 and the curved portion 27 which join the flat apices 25 to the original plane of the plate 28.

5 Fig. 11 shows the minor corrugations 22 pressed in an opposite direction within the major corrugations 21 midway between the center and termination of the corrugations at 23.

10 Fig. 12 shows the uniform, contiguous and sinuous convergence of the major and minor corrugations just before merging into the original plane 28 of the plate 20.

15 Figs. 13, 14 and 15 are detailed enlargements of a modified form of corrugation similar to Figs. 10, 11 and 12.

20 Figs. 16, 17, 18, 19 and 20 show a modified detail of a plate in which 50 is the plate, 51 is the major corrugation of uniform width and depth and 52 is the minor corrugation of varying width and depth that lies within the major corrugation 51 and is oppositely disposed. The major corrugations have flat apices 53 decreasing in width and gradually merging into the divergent extremities thereof. The flat apices 53 are joined to the original plane of the plate by sloping sides 54 and curves 55. The corrugations merge into the plane 57 of the plate 50 by means of termination 56. The upper minor corrugations are preferably longer than the lower minor corrugations so that the maximum strength of the plate is nearer to one edge than the other. In this modification the embossments have 35 parallel sides.

Fig. 17 is a top edge view of Fig. 16 and shows the major corrugation 51 of uniform depth while the minor corrugation 52 is shown merging from the plane 57 of the plate 40 50 into the major corrugation 51 at the center thereof.

45 The major and minor corrugations merge together at their extremities 58 forming a sinuous configuration before terminating into the original plane 57 of the plate 50.

Fig. 18 is a cross section taken on line 18—18 of Fig. 16 showing the relatively wide major corrugations 51.

50 Fig. 19 is a cross section taken on line 19—19 of Fig. 16 showing minor corrugations 52 pressed in an opposite direction to that of the major corrugation 51 in effect bifurcating the major corrugation 51 at 58.

55 Fig. 20 is a cross section taken on line 20—20 of Fig. 16 showing the convergence of major and minor corrugations just before terminating into the original plane 57 of the plate 50.

60 Figs. 21, 22, 23, 24 and 25 show a modified detail of a plate in which 60 is the plate, 61 is the major corrugation of uniform depth and increasing width toward its extremities 62, and 63 are the minor corrugations of varying depth and width dividing the major corrugations 61 at its extremities 62 forming in

effect a plurality of divergent uniform corrugations just before terminating into the original plane 64 of the plate 60. The long axis of the terminals 65 are in alignment with the longitudinal axis of the corrugations. The upper minor corrugations are preferably longer than the lower minor corrugations so that the maximum strength of the plate is nearer to one edge than the other.

70 Fig. 22 is a top edge view of Fig. 21 showing the major corrugations 61 of uniform depth and the minor corrugations 63 tapering in depth from the apices 66 of the major corrugations 61 to the original plane 64 of the plate 60.

75 Fig. 23 is a cross section taken on line 23—23 of Fig. 22 showing the major corrugations 61 and valleys 67 of uniform width and depth, while the major corrugations 61 increase in width and merge into a plurality of divergent corrugations. The valleys 67 decrease in width toward the edges of the plate 60.

80 Fig. 24 is a cross section taken on line 24—24 of Fig. 21 showing the minor corrugations 63 pressed within and in opposite direction to that of the major corrugation 61.

85 Fig. 25 is a cross section taken on line 25—25 of Fig. 21 showing the convergence of the major and minor corrugations of uniform and sinuous formation just before terminating into the original plane 64 of the plate 60.

90 Figs. 26, 27, 28, 29 and 30 show a modified detail of a plate in which 70 is the plate, 71 is the major corrugation of varying width, being widest at its extremities 72. 73 is the minor corrugation varying in depth and width lying within the major corrugation 71 and in effect dividing or splitting the major corrugation 71 into a plurality of corrugations of uniform depth and width and of a contiguous and sinuous formation, as at 30—30. The corrugations are of constant cross section for a short distance, the object 95 being to form a corrugated plate of greater strength for a wider portion of the plate and also to facilitate the changing of the dies used for forming the corrugations. The upper minor corrugations are preferably longer 100 than the lower minor corrugations so that the maximum strength of the plate is nearer to one edge than the other.

105 Fig. 27 is a top edge view of Fig. 26 showing the major corrugation 71 and the minor corrugation 73 tapering in depth from the apices 74 of the major corrugation to the original plane 75 of the plate 70.

110 Fig. 28 is a cross section taken on line 28—28 of Fig. 26 showing the major corrugations 71 of uniform depth and width at the center of the sheet.

115 Fig. 29 is a cross section taken on line 29—29 of Fig. 26 showing the minor corrugation 73 pressed within and in opposite direction to 120

that of the major corrugation 71, and the cross sectional area is the same as section 28—28.

Fig. 30 is a cross section taken on line 30—30 of Fig. 26 showing the convergence of the major and minor corrugations of uniform and sinuous formation just before terminating into the original plane 75 of the plate 70, and the cross sectional area is the same as sections 28—28 and 29—29.

A plate provided with a plurality of contiguous narrow corrugations possess a considerable amount of elasticity and when struck a blow deflects readily and regains its shape without distortion, whereas a plate provided with wide flat corrugations though better able to carry quiescent loads has not the resiliency of the former and is more readily distorted when struck a blow.

I have described and claimed the corrugations as being that portion of the reinforcement between the terminations or between lines corresponding to 9—9 in Fig. 5, the terminations are the conical or pointed portions, such as 31 in Fig. 5.

It is, therefore, desirable to design a plate that possesses great strength to withstand the sudden impact loads or blows, with sufficient resiliency to resist distortion.

This application is confined to the construction wherein the minor corrugations merge to form the major corrugation, whereas in my application, Serial No. 55,207, filed September 8, 1925, I have shown and claimed a construction wherein the major corrugation is split into two or more minor corrugations.

This is a continuation in part of my application Serial No. 595,634 filed October 19, 1922.

I claim:

1. A wall structure for a railway car comprising a metallic plate provided with a plurality of vertical corrugations spaced apart distances substantially equal to their width, said corrugations merging between their ends adjacent the floor of the car into a plurality of fewer corrugations spaced apart distances substantially equal to their width.

2. A wall structure for a railway car comprising a metallic plate provided with a plurality of vertical corrugations spaced apart distances substantially equal to their width, said corrugations merging between their ends adjacent the floor of the car into a plurality of fewer wider corrugations spaced apart distances substantially equal to their width.

3. A metallic plate wall structure provided with a plurality of vertical corrugations merging adjacent the floor of the car into a lesser number of wider corrugations, the maximum strength of the corrugated wall being below the middle of the corrugated portion of the plate.

4. A wall structure for a railway car com-

prising a metallic plate provided with a plurality of vertical corrugations symmetrical in cross section about a line midway between the outermost portions of the corrugations, said corrugations merging between their ends adjacent the floor of the car into a plurality of fewer vertical corrugations symmetrical in cross section about a line midway between the outermost portions of the corrugations.

5. A wall structure for a railway car comprising a metallic plate provided with a plurality of vertical corrugations symmetrical in cross section about a line midway between the outermost portions of the corrugations, said corrugations merging between their ends adjacent the floor of the car into a plurality of fewer wider vertical corrugations symmetrical in cross section about a line midway between the outermost portions of the corrugations.

6. A wall for a railway car comprising a metallic plate secured to oppositely disposed horizontal frame members of the car, said plate provided with a plurality of vertical corrugations with their opposite ends terminating into the plate adjacent said oppositely disposed frame members, said corrugations merging together between their ends adjacent the lower of said frame members to form a plurality of fewer, wider corrugations.

7. A wall for a railway car comprising a metallic plate secured to oppositely disposed horizontal frame members of the car, said plate provided with a plurality of vertical corrugations spaced apart distances substantially equal to their width with their opposite ends terminating into the plate adjacent said oppositely disposed frame members, said corrugations merging together between their ends adjacent the lower of said frame members to form a plurality of fewer corrugations spaced apart distances substantially equal to their width.

8. A wall for a railway car comprising a metallic plate secured to oppositely disposed horizontal frame members of the car, said plate provided with a plurality of vertical corrugations spaced apart distances substantially equal to their width with their opposite ends terminating into the plate adjacent said oppositely disposed frame members, said corrugations merging together between their ends adjacent the lower of said frame members to form a plurality of fewer, wider corrugations spaced apart distances substantially equal to their width.

9. A wall for a railway car comprising a metallic plate secured to oppositely disposed horizontal frame members of the car, said plate provided with a plurality of vertical corrugations symmetrical in cross section about a line midway between the outermost portions of the corrugations with their opposite ends terminating into the plate adjacent said oppositely disposed frame members,

said corrugations merging together between their ends adjacent the lower of said frame members to form a plurality of fewer corrugations symmetrical in cross section about a line midway between the outermost portions of the corrugations.

10. A wall for a railway car comprising a metallic plate secured to oppositely disposed horizontal frame members of the car, said plate provided with a plurality of vertical corrugations symmetrical in cross section about a line midway between the outermost portions of the corrugations with their opposite ends terminating into the plate adjacent
- 15 said oppositely disposed frame members, said corrugations merging together between their ends adjacent the lower of said frame members to form a plurality of fewer, wider corrugations symmetrical in cross section about a line midway between the outermost portions of the corrugations.
- 20 11. A wall for a railway car comprising a metallic plate secured to oppositely disposed horizontal frame members of the car, said plate provided with a plurality of vertical sinuous and contiguous corrugations with their opposite ends terminating into the plate adjacent said oppositely disposed frame members, said corrugations merging together

- 25 between their ends adjacent the lower of said frame members to form a plurality of fewer corrugations with substantially flat apices.

12. A wall for a railway car comprising a metallic plate secured to oppositely disposed horizontal frame members of the car, said plate provided with a plurality of vertical sinuous and contiguous corrugations with their opposite ends terminating into the plate adjacent said oppositely disposed frame

members, said corrugations merging together between their ends adjacent the lower of said frame members to form a plurality of fewer, wider corrugations with substantially flat apices.

13. A wall for a railway car comprising a metallic plate secured to oppositely disposed horizontal frame members of the car, said plate provided with a plurality of vertical corrugations spaced apart distances substantially equal to their width symmetrical in cross section about a line midway between the outermost portions of the corrugations with their opposite ends terminating into the plate adjacent said oppositely disposed frame members, said corrugations merging together

50 between their ends adjacent the lower of said frame members to form a plurality of fewer, wider corrugations spaced apart distances substantially equal to their width symmetrical in cross section about a line midway between the outermost portions of the corrugations.

14. A metallic structure for a railway car comprising a metallic plate secured to oppositely disposed horizontal frame members of the structure, said plate provided with a plurality of arcuate vertical corrugations of constant depth with the parts of the plate between said corrugations also of arcuate configuration, said corrugations merging together between their ends to form a plurality of fewer vertical corrugations having substantially flat apices with the parts of the plate between the last mentioned corrugations also being substantially flat, said corrugations terminating into the plate adjacent said oppositely disposed frame members.

ARTHUR E. SMALL.
